UNITED STATES PATENT OFFICE

164,837

SEWING-MACHINE CABINET

Adam Baker Barnhart, New York, N. Y., assignor
to The Singer Manufacturing Company, Eliza-
beth, N. J., a corporation of New Jersey

Application August 3, 1951, Serial No. 16,142

Term of patent 14 years

(Cl. D33—12)

To all whom it may concern:

Be it known that I, Adam Baker Barnhart, a citizen of the United States, residing at New York, in the county of New York and State of New York, have invented a new, original, and ornamental Design for a Sewing-Machine Cabinet, of which the following is a specification, reference being had to the accompanying drawings, forming a part thereof.

Fig. 1 is a perspective view looking toward the left front corner of a sewing-machine cabinet in closed condition which incorporates my novel design.

Fig. 2 is a perspective view looking toward the right rear corner of the cabinet, also in closed condition.

Fig. 3 is a perspective view of the cabinet in its open condition.

I claim:

The ornamental design for a sewing-machine cabinet, substantially as shown.

ADAM BAKER BARNHART.
